UNITED STATES PATENT OFFICE

109,163

DESIGN FOR A CONTAINER FOR A DRINKING RECEPTACLE OR SIMILAR ARTICLE

Peter J. Swofford, Arlington, Tex.

Application August 19, 1937, Serial No. 71,206

Term of patent 14 years

To all whom it may concern:

Be it known that I, Peter J. Swofford, a citizen of the United States, residing in Arlington, in the county of Tarrant and State of Texas, have invented a new, original, and ornamental Design for a Container for a Drinking Receptacle or Similar Article, of which the following is a specification, reference being had to the accompanying drawing forming part thereof, in which:

for a drinking receptacle or similar article, showing my new design;

I claim:

The ornamental design for a container for a drinking receptacle or similar article, as shown.

PETER J. SWOFFORD.
